UNITED STATES PATENT OFFICE.

FRED J. HEIDEMAN, OF DETROIT, MICHIGAN, ASSIGNOR TO KELVINATOR CORPORATION, OF WILMINGTON, DELAWARE, A CORPORATION OF DELAWARE.

FITTING FOR REFRIGERATING MACHINERY.

1,384,753.

Specification of Letters Patent. Patented Mar. 23, 1920.

Application filed July 22, 1918. Serial No. 246,236.

To all whom it may concern:

Be it known that I, FRED J. HEIDEMAN, a citizen of the United States, residing at Detroit, in the county of Wayne and State 5 of Michigan, have invented a certain new and useful Improvement in Fittings for Refrigerating Machinery, of which the following is a full, clear, and exact description, reference being had to the accompanying drawings.

This invention relates to valved fittings and has especial reference to a fitting for use with a refrigerating apparatus, although not necessarily restricted thereto. The objects of the invention are the provision of a fitting of simple and leak-proof construction including certain valve means whereby the main system may either be shut off or may be connected to a suitable side branch 20 as for filling, emptying, or testing; the provision of valves of such construction as to enable the compressor to be removed at will without draining the refrigerating system; while further objects and advantages of the 25 invention will become apparent as the description proceeds.

In the drawings accompanying and forming a part of this application I have shown a preferred embodiment of my invention, 30 both separately and in place in a refrigerating system in operative relation to the compressor; although it will be understood that these drawings are illustrative merely and do not limit me to any of the constructions or arrangements therein shown since my invention may be embodied in numerous physical forms. In these drawings Figure 1 illustrates a preferred type of compressor having my improved fittings connected 40 thereto, the remainder of the refrigerating system being illustrated diagrammatically; Fig. 2 is a longitudinal sectional view through my improved fitting; and Fig. 3 is a top plan view of the same.

In the drawings, 1 represents the cylinder of a compressor, 2 the piston, 3 the crank shaft, 4 the crank casing, and 5 the cylinder head. This compressor is of the two-cycle type, the side of the cylinder being 50 formed with a port 6 communicating with the crank case by a passageway, not shown. So far as the present invention is concerned the particular construction of the compressor is not important, but a typical compres-

sor is shown so as to illustrate the use of my improved fitting.

My improved fitting consists of a body 10 having therein a longitudinal bore 11 intersected by a recess 12. One side of the body is formed with an attaching flange 13 60 presenting a flat face 14 through which the recess 12 opens, and by means of which the body can be attached either to a boss 15 carried by the crank casing or to the cylinder head 5 as shown in Fig. 1. At one end 65 of the bore 11 the body is formed for the attachment of a flexible pipe 16, being in the present instance externally threaded as at 17 for the reception of a screw thimble 18. Upon the other side of the recess 12 from the bore 11, and coaxial with that bore, 70 the body is formed with a threaded aperture for the reception of the valve bonnet 20 in which is mounted the threaded stem 21 whose inner end is provided with 75 a head 22 adapted to seat upon the end of the bore 11 and close it.

The body is also formed with a threaded socket 25 adapted to receive either a closing plug 26 or a suitable pipe member as 27. This 80 socket communicates with the recess 12 by means of an independent passageway 28, and means are provided for closing this passageway from the inside, the means here shown comprising a needle valve 29, threaded into 85 a boss 30 opposite that passageway. The stems 21 and 29 are here shown as surrounded by packing glands 31 whereby leakage of the refrigerant is prevented.

The parts 27 may either be the stems of 90 pressure gages as shown, or they may be conduits connecting the fittings either with a reservoir of refrigerant or a place for the discharge of the same. The provision of valve means for the passageway 28 enables the prevention of leakage while substituting a pipe for a plug or vice versa. In practice the pressure gages are not ordinarily left connected but are applied temporarily as necessary for the inspection or 100 testing of the system. This system generally consists of a suitable refrigerating coil 40 having one of its ends connected to the pipe 16 of the fitting applied to the cylinder head, and having its opposite end 105 connected to the expansion valve 41. To the other side of the expansion valve is attached the expansion coil 42, whose op-

posite terminal is attached to the pipe 16 of the fitting connected to the compressor crank case. It will be seen that by closing the two valves 21—29 the compressor can be removed bodily from the system without loss of refrigerant; that by substituting an exhaust pipe for the plug 26, which is at the pressure side of the compressor, opening the corresponding valve 29 and closing the corresponding valve 21, the refrigerant can be drained thoroughly from the system, merely by operating the compressor in the usual manner, either into a storage tank or into some place of discharge and without the escape of objectionable fumes. It will also be seen that by attaching a refrigerant receptacle in place of the plug 26 which is at the inlet side of the compressor, opening the corresponding valve 29 and closing the corresponding valve 21, the system can be charged with refrigerant to any desired degree merely by running the compressor. It is also easy with this arrangement to attach a pressure gage temporarily for the purpose of testing the system as is desirable from time to time and without danger that refrigerant will escape.

It will be understood that the present drawings and descriptions are illustrative of only one out of a great number of physical structures in which my improvements can be embodied, wherefore great changes can be made within the scope of the claims hereto annexed.

Having thus described my invention, what I claim is:—

1. In a device of the character described, a body having a pair of parallel longitudinal bores, a transverse recess intersecting said bores, each of said longitudinal bores

having a valve member at one end and a threaded portion at the other end.

2. In a device of the character described, a body having a pair of parallel longitudinal bores, a transverse recess intersecting said bores, a threaded portion and valve seat at one end of each of said bores and a valve member at the other end of each of said bores for cooperating with said seat.

3. In a device of the character described, a body having a transverse recess and a longitudinal bore intersecting said recess, said body having a threaded aperture at one end of said bore and in alignment therewith, a bonnet seated in said aperture, a valve member carried by said bonnet and adapted to close said bore, a threaded socket at the other end of said bore adapted to receive a pipe member, a flange at the side of said body parallel to said bore and surrounding said recess, and a threaded socket carried by said body adapted to receive either a closing plug or a pipe member, said socket communicating with said recess by means of a valve-controlled passage.

4. In a device of the character described, a body having an attaching face and a pair of parallel bores, said body also having a recess opening through said face and intersecting said bores, a valve member threaded into that side of each bore which lies on one side of said recess and adapted to enter and close the opposite portions of the corresponding bore, and means for attaching a pipe to the portion of each bore opposite said valve members.

In testimony whereof, I hereunto affix my signature.

FRED J. HEIDEMAN.
